[57] CLAIM

The ornamental design for an equipment housing, as shown and described.

DESCRIPTION

FIG. 1 is a front perspective view of an equipment housing incorporating our new design;

FIG. 2 is a front elevational view of the housing of FIG. 1;

FIG. 3 is a top plan view of the housing of FIG. 1;

FIG. 4 is a left side elevational view of the housing of FIG. 1;

FIG. 5 is a rear elevational view of the housing of FIG. 1;

FIG. 6 is a bottom plan view of the housing of FIG. 1;

FIG. 7 is a front right top perspective view of a second embodiment of the equipment housing incorporating our new design;

FIG. 8 is a front elevational view of the housing of FIG. 7;

FIG. 9 is a top plan view of the housing of FIG. 7;

FIG. 10 is a left side elevational view of the housing of FIG. 7;

FIG. 11 is a rear elevational view of the housing of FIG. 7; and,

FIG. 12 is a bottom plan view of the housing of FIG. 7.
